UNITED STATES PATENT OFFICE.

LEWIS C. MYERS, OF FREEPORT, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed February 12, 1922. Serial No. 618,576.

To all whom it may concern:

Be it known that I, LEWIS C. MYERS, a citizen of the United States, residing in Freeport, in the county of Nassau and State of New York, have invented certain new and useful Improvements in Typewriting Machines, of which the following is a specification.

This invention relates to typewriting machines in which there is a relative movement between the printing members and the platen for case printing. In some machines the platen is shifted for this purpose, while in others the type bars with their segment or support are thus shifted.

In the Royal machine, the platen is supported in a carriage which is shifted vertically for case printing, one or more shift keys being connected with the carriage by mechanism which normally holds the carriage in lower position, but which when a shift key is depressed causes the carriage and its platen to be raised to upper case position. In the Royal machine in order to partially counterbalance the weight of the carriage so that the load on the shift keys may be reduced, a spring is connected with the shift mechanism and is put under such tension as to tend to raise the carriage and to thus assist in the shifting operation. In the Royal standard machine, the carriage is returned to normal position solely by gravity and the counterbalancing spring has been of such tension that it will not so overcome the force of gravity as to prevent or unduly impede the return of the carriage.

In the pending application filed by Edward B. Hess Jan. 13, 1923, No. 612,462, and the pending application of Bernard J. Dowd filed Jan. 11, 1923, No. 612,117, mechanism is shown, described and claimed whereby an initial impulse is given to the return movement of the carriage. In this way the return of the carriage is quickened and the strength of the counterbalancing spring may be increased so that the shift key may be operated with a lighter touch.

Although my invention is applicable to typewriting machines generally in which there is a relative movement between the printing members and the platen, it is particularly serviceable in machines of the Royal type in which the platen is mounted in a carriage which is shifted vertically for case printing.

An important feature of my invention consists in the provision of a repulser which is normally inactive, is completely energized after the completion of the shifting movement and becomes active before acting upon the shifted part. Preferably a coiled spring is used for this purpose, the spring being normally inactive or substantially so, the tension being partially increased during the shifting operation and fully increased after the shifting operation is completed. In this way when the shift key is released the tension of the spring is quickly relaxed before acting upon the shifted part and thus a sudden impulse is given to the return movement of said shifted part, which is found to facilitate the operation.

The mechanism containing the preferred embodiment of my invention provides means whereby the shift key is cushioned during its depression and whereby the repulser spring is tensioned during the cushioning period.

It may be noted that the more rapid the operator of the machine, the greater necessity there is of having the shifted part return quickly to normal position. Furthermore the rapid operator is more likely to strike the case with considerable force. In the preferred embodiment of my invention, the repulser spring is tensioned to a greater extent if the shift key is depressed to its full extent, which is likely to be the case when a heavy blow is imparted to the key. Therefore the repulser spring when thus tensioned will exert a greater force at the commencement of the return movement of the platen than if the key were lightly depressed and the repulser spring not given its full extension.

The means whereby these results may be obtained are illustrated in the accompanying drawings, in which:—

Figure 1 is a view partly in side elevation and partly in section of parts of a Royal typewriting machine, showing substantially the usual form of shift mechanism with my invention included. All parts are shown in lower case position.

Figure 2 is a plan view showing a pair of shift keys with the usual Royal rock shaft enabling operation of the shift mechanism from either side of the machine.

Figure 3 is a side elevation of the essential parts of the mechanism showing by full lines these parts in shifted position and by dotted lines the position of some of the parts during the cushioning period.

Figure 4 is a side elevation of a modified form of mechanism.

Figure 5 is a side elevation of shift mechanism similar to that shown in the Dowd application above mentioned with my improvements added. The parts are shown by full lines in shifted position and dotted lines indicate the normal position of the shift key.

Figure 6 is a view similar to Figure 5 showing the position of the essential parts of the mechanism during the cushioning period or at the end of the movement of the shift key.

Figures 7, 8, and 9 are diagrammatic views.

Figure 7 shows the position of the repulser spring and repulser arm when in normal position.

Figure 8 shows the position of these parts when the platen is fully shifted.

Figure 9 shows their position at the end of the cushioning period.

Figures 10, 11, and 12 show a further modification in which the repulser is arranged at the right hand side of the machine and is operatively connected with parts of the shift mechanism at the right hand side of the mechanism.

Figure 10 shows the position of the parts in normal position.

Figure 11 shows these parts in shifted position.

Figure 12 shows their position during the cushioning period.

The drawings disclose only so much of the typewriting machine structure as is necessary to indicate how my invention may be applied to the preferred form of machine. The main frame is indicated at A, the carriage at B, and the platen at C. The shift rail D has downwardly extending legs E connected near their lower ends to links F which are pivotally connected at f to the machine frame. The upper parts of the legs are pivotally connected with rocker arms H mounted on a rock shaft h.

The shift key K in the form shown in

Figures 1 and 3 has an upwardly extending arm k to which is pivoted at k' a bell crank lever K', the lower substantially horizontal arm of which terminates in a roller K² adapted to engage the lower end of one of the legs E of the shift rail. The vertical arm K³ of the lever K' is connected by a link N to a latch O adapted to engage a bracket P on one of the legs E to hold the carriage in lower position. While the shift key is depressed, owing to certain lost motion between the roller K² and the leg E, the latch is withdrawn before the mechanism commences to raise the carriage. A spring k² connects the upper part of the arm k to the extension k⁵ of the lever K' and serves to cause the shift key lever and the lever K' to move together during the shifting movement, but permits a further cushioning movement of the shift key after the carriage is fully shifted. In order to hold the carriage in upper case position, I preferably employ the usual dog Q which is normally inactive but which engages the bracket P and holds the carriage in raised position when the shift lock key Q' is operated. The shift lock mechanism indicated at Q² is of usual construction and is operated in the usual way.

The weight of the carriage, in the construction shown, is partially counterbalanced by a spring T connected with the machine frame and with the shift mechanism. This spring is normally under tension and tends to do so, although it facilitates in the lifting operation of the shift key. When the carriage is raised to its full extent, the tension of the spring is fully relaxed and when the shift key is released the carriage returns solely by gravity, the preponderance of the weight of the carriage over the lifting force exerted by the spring having been heretofore relied on for this purpose. The spring T is connected at one end to a toothed plate U pivoted at u to the frame of the machine and adjusted by means of a screw U'.

When a shift key is depressed, the latch O is first released, after which the carriage is raised to its full extent against a stop B' and the tension of the spring T is relaxed. As soon as the shift key or shift lock key is released, the carriage returns by gravity to its lower position determined by a stop A'. The construction and operation above described is similar to that shown in other machines.

An object of my present invention is to provide a repulser which generically is similar to that shown in the Hess and Dowd applications above referred to. The improved repulser is normally inactive and becomes active or effective at the time the platen commences its return movement, being just prior to this disconnected operative-

ly from the shift mechanism so that it acquires some momentum before engaging the shift mechanism and thus imparts a sudden impulse to the mechanism which causes 5 it to start promptly and to continue quickly in lowering the platen.

There are several ways in which the results last mentioned may be obtained. In 10 Figures 1 and 3 I have shown an arm or lever L having an upwardly extending portion at its forward end terminating in an offset l which overlies one of the links F but is normally out of contact therewith. The arm L has an extension on its lower 15 side carrying a roller L' which is disposed above the rear portion of an extension K⁴ on the shift key lever. A spring l' having one end fastened to the arm L and the other end connected to an adjustable eccentric m' 20 on the bracket or housing M is normally inactive or relaxed and the arm L rests at this time on an eccentric stop m². In this form of mechanism, the depression of a shift key will cause the carriage and related parts 25 to be raised in the manner before described. As shown by full lines in Figure 3, where the carriage has been shifted to its full extent, the arm L will have been engaged by the associated link F and moved a slight 30 distance, thus imparting or adding some tension to the spring l'. If the shift key is depressed no further but then released, the spring will exert an immediate effect to initiate the carriage return, but if the shift 35 key is further depressed and moved from the full line position shown in Figure 3 to the dotted position there shown, the repulser arm L will move to the dotted position indicated in which position its front end lies 40 considerably above the associated link F and the spring l' will be tensioned to a much greater extent.

As soon as the shift key is released, the arm L will move downwardly very quickly, 45 will strike against the repulser arm suddenly, and quickly start the return movement of the carriage and thereby materially assist gravity in the completion of the return movement.

50 Figure 4 shows a modification in which the offset part l of the arm L overlies a lever L² pivoted to the machine frame at l² and provided at its front end with a roller L³. The shift lever is provided with a 55 short extension K⁵ which projects under the roller L³. The lever L² is adapted to engage the adjacent leg E and the carriage is thus shifted when the shift key is depressed. While a dog Q for holding the 60 carriage in upper position is shown in Figure 3, its operating mechanism is omitted. The operation of the mechanism shown in Figure 4 is similar to that shown in Figures 1 and 3, the spring l' being tensioned in a 65 similar manner but acting only to give the

shift key a quick initial impulse toward normal position. Some of the mechanism shown in Figure 4 is similar to that shown in Figures 1 and 3 and the corresponding parts are similarly lettered.

In the modified form of the invention shown in Figures 5 to 9 inclusive, a counter-balancing spring is employed of the kind shown in the application of Bernard J. Dowd above mentioned, i. e., a spring which 70 is so connected with the shift mechanism that it operates also to give an initial impulse to the return movement of the carriage, but such spring according to my invention is used in connection with other devices next 75 to be described.

The upwardly extending arm l of the shift key lever is connected by a link R to another link R' in turn connected to a pin v' on the lower end of the cushion setting 80 member V which is pivoted at v to one of the rocker arms H. The member V has an upwardly extending arm v³ carrying a pin v⁴ working in a slot h' in the rocker arm H. When the shift key is depressed 85 a pull is exerted on the links R, R' and through the member V the arm H is rocked about its pivot h thereby shifting the parts.

The counterbalancing spring T', it will 90 be observed, is connected at one end to the tension regulating member U and at the other end to a pin v² on the member V. This member is similar to that shown in the Dowd application and operates in the same 95 way. It provided for giving an initial impulse to the carriage during its return movement, but I have found it desirable to supplement the operation by devices which are normally inactive but which impart a quick or sudden impulse to the return movement 100 of the carriage at the commencement of its return movement, these devices thus co-operating with the spring T' and with gravity in effecting the return movement.

A bell crank lever L⁴ is pivoted at m to 110 the machine frame and has a forwardly extending upper arm carrying a roller l⁴ which overlies the adjacent link F. The lower arm of the lever L⁴ carries at its free front end a roller L⁶ which overlies an extension 115 K⁴ on the shift lever. The tension spring l' is attached to this lower arm and to a pin m' and the arm rests on an eccentric stop m² by which the position of the bell crank 120 may be adjusted. The adjustment is normally such that the rollers l⁴ and L⁶ will be at some distance above the adjacent link F and the extension K⁴ of the shift key lever.

When the shift key is depressed from the 125 normal dotted position shown in Figure 5 to the full line position shown in the same figure, the carriage is moved to shifted position. During this operation the lever L⁴ is moved slightly as indicated by full lines, but the roller l⁴ is just out of contact with 130

the arm L^4 or exerts no material force thereon. In this form of the shift mechanism the cushioning movement of the shift key is permitted by the lost movement at h' and v^4 and the particular mounting of the spring T' , which spring acts as the cushioning spring as well as a counterbalancing spring. In this cushion period, the carriage remains stationary, but the shift key lever and associated parts move to the position shown in Figure 6. At this time it will be noted, the roller l^4 lies considerably above the link F and the spring l' has been put under considerable tension.

Figures 7, 8, and 9 show diagrammatically the relative positions of the associated parts of the mechanism with regard to the link F in the different positions mentioned, viz., normal position, carriage shift position, and cushion period position.

As soon as the shift key is released, the spring l' causes the roller l^4 to be moved into engagement with the link F , thus giving the mechanism a quick blow and a quick start towards normal position. The spring T' , it is true, gives an initial impulse to the return movement of the carriage, but the spring l' comes into operation at substantially the same time and supplements the action of the spring T' and thus insures prompt action. The eccentric stop m^2 may be so adjusted as to vary the normal position of the lever L^4 and regulate its actions. The spring l' may be adjusted as desired to vary its strength in any suitable way.

A single shift key may be employed or I may use two shift keys connected by a rock shaft X as shown in Figure 2 so that the shift mechanism may be operated from either sides of the machine.

Figures 10, 11, and 12 illustrate a modification in which the connection between the key lever and the bell crank lever L^4 is made at the right hand side of the machine. The carriage lifting devices are not shown in these figures of the drawings as they are located at the left hand side of the machine. The upwardly extending arm W of the shift key lever at the right of the machine is connected by a link W' to the bell crank lever L^4 . The link W' terminates in a loop w which engages a pin L^7 on the lower arm of the lever L^4 . In other respects the construction and operation are similar to those before described.

Figure 10 shows the mechanism in normal position, the carriage shift mechanism being below the stop B' and the roller l^4 above the link F .

Figure 11 shows the position of the parts when the carriage has been raised to its full extent, limited by the stop B' , the roller l^4 being in contact with the adjacent link F .

In Figure 12 the shift key is moved to its full extent during the cushion period,

the lever l^4 having been raised above the link F .

When the shift key is released, the force of gravity and the repulser mechanism described co-operate to return the carriage. The roller l^4 gives a sudden quick blow to the link F , thus insuring against any lagging in the return movement and imparting a sudden and positive force in accomplishing the quick return movement of the mechanism.

It will be observed that in all cases the repulser device such as the arm L' or the arm L^4 is normally out of contact with the adjacent link F or with any part of the carriage shift mechanism and the repulser spring l' has no effect on the shift mechanism. The arm L or L^4 is also out of contact with any part of the carriage shift mechanism at the end of the cushioning movement of the shift key. Said arm makes contact with the shift mechanism only during a portion of the shifting movement of the carriage.

A characteristic feature of the invention is a repulser which is given increased effective energy mainly during the cushion period or after the carriage has been shifted. The repulser is entirely independent of the carriage shift mechanism when the parts are in normal position, but it is controlled thereby.

In mechanism of the character described where there is an advanced movement of the repulser before the shifting mechanism commences its return movement, there is no need to place entire dependency upon gravity for the return of the carriage and the balancing spring can therefore be adjusted in such manner that the touch on the shift key may be lightened. This enables the counterbalancing spring which also serves as a repulser spring to be tensioned at the end of the shift key movement when the key has acquired considerable momentum and this does not require the touch of the shift key to be as heavy as if the spring had to be overcome from the beginning of the movement of the key as in the case of an ordinary return spring.

As before stated, the principle involved in my invention is applicable to various types of shift mechanism, including those in which the whole carriage is shifted, those in which a smaller supplemental carriage is shifted in the lower carriage, and those in which the type bar segment or printing members are shifted relatively to the platen. While preferably forming its greatest value in a machine in which the shifted member is moved vertically it may also be used where the shifted member travels in a different direction.

I claim as my invention:

1. In a typewriting machine a case shift mechanism comprising a case shift key, a repulser mechanism and means operated by

- the depression of the shift key to its full extent to move the repulser mechanism to a position from which it moves rapidly into engagement with the shift mechanism as soon as the key is released and thus imparts a sudden initial impulse to the return movement of the shifted part.
6. In a typewriting machine, printing members associated with a platen, means for effecting relative case shift movement between them, repulser mechanism for the shifted part, and means to fully energize the repulser mechanism after the completion of the shifted movement, said mechanism beginning its return movement before operating upon the shifted part.
7. In a typewriting machine printing members associated with a platen, means for effecting relative case shifting movement between them, repulser mechanism for the shifted part and means to render said repulser mechanism active before the shifted part commences to return and thereby impart a sudden impulse to the returning part.
8. In a typewriting machine type bars associated with a platen, means for shifting the platen for case printing, a spring for partially counterbalancing the platen, repulser mechanism for the shifted part and means for energizing said repulser mechanism after the completion of the shifting movement and permitting it to become active before operating upon the shifted part.
9. In a typewriting machine, printing members associated with a platen, means for effecting relative case shifting movement between the spring actuated repulser mechanism and the shifted part, and means for energizing said repulser mechanism after the completion of the shifting movement and permitting it to become active before operating upon the shifted part.
10. In a typewriting machine, type bars associated with a platen, means for effecting relative case shift movement between them, repulser mechanism for the shifted part, and means to fully energize the repulser mechanism after the completion of the shifted movement, said mechanism beginning its return movement before operating upon the shifted part.
11. In a typewriting machine, type bars associated with a platen, platen shift mechanism, a shift key connected with such mechanism and which has a rearwardly extending part between a pivoted repulser arm adapted to engage the shift mechanism, a normally relaxed spring and means for increasing the tension thereof after the shifting operation is completed and permitting it to be partially relaxed before acting to give a sudden impulse to the return movement of the shifted part.
12. In a typewriting machine, type bars associated with a platen, platen shift mechanism, a shift key connected with such mechanism and which has a rearwardly extending part between a pivoted repulser arm adapted to engage the shift mechanism, a normally relaxed spring and means for increasing the tension thereof after the completion of the shifting movement and permitting it to suddenly engage the shift mechanism upon the release of the shift key to thereby give a quick impulse to the return movement of the platen.
13. In a typewriting machine, type bars associated with a platen, a spring for partially counterbalancing the weight of the platen, shift mechanism for the platen, a repulser operating independently of said spring and means for fully energizing said repulser after the completion of the shift movement of the platen.
14. In a typewriting machine, type bars associated with a platen, a spring for partially counterbalancing the weight of the platen, shift mechanism for the platen, a repulser operating independently of said spring and means for fully energizing said repulser after the completion of the shift movement of the platen.
15. In a typewriting machine, a partially balancing carriage shift mechanism therefor, repulser mechanism normally disconnected from the shift mechanism and the carriage and means for fully energizing said repulser mechanism after the completion of the shift movement of the carriage to give an initial impulse to the return movement thereof.
16. In a typewriting machine, a partially balancing carriage shift mechanism therefor including a shift key which has a movement after the completion of the carriage shift repulser mechanism and means for fully energizing said repulser mechanism during such further movement and causing it to give an initial impulse to the return movement of the carriage.
17. In a typewriting machine, a partially balanced carriage, shift mechanism therefor, repulser mechanism normally disconnected from the shift mechanism, and means whereby the shift mechanism energizes the repulser mechanism.
18. In a typewriting machine, a partially balanced carriage, shift mechanism therefor including a shift key lever, repulser mechanism normally disconnected from the shift mechanism, and an extension on said shift key lever operatively connected with the repulser mechanism to energize the repulser mechanism during the latter part of the movement of the shift key.
19. In a typewriting machine, printing members associated with a platen, means for effecting relative case shift movement between the two,

repulser mechanism for the shifted part and means for fully energizing said repulser mechanism after the completion of the shift movement and permitting it to become active before the return movement of the shifted part commences.

16. In a typewriting machine, a carriage, a balancing spring therefor, a shift key, means whereby said balancing spring affords a cushioned period for the shift key, a repulser and means for fully energizing said repulser during the cushioned period where-

by it acts to give an initial impulse to the return movement of the carriage.

17. In a typewriting machine, a carriage 18 mounted for vertical movement, a carriage shift rail on which the carriage rests having a leg depending from it, and shift mechanism comprising a key lever and a pivoted extension thereon adapted to engage said 20 leg and lift the shift rail.

In testimony whereof, I have hereunto subscribed my name.

LEWIS C. MYERS.
